(57) **CLAIM**

The ornamental design for a bin, as shown and described.

DESCRIPTION

FIG. 1 is a front perspective view of a bin of the present invention.

FIG. 2 is a bottom perspective view of FIG. 1.

FIG. 3 is a top view of FIG. 1.

FIG. 4 is a bottom view of FIG. 1.

FIG. 5 is a front view of FIG. 1.

FIG. 6 is a rear view of FIG. 1.

FIG. 7 is a left side view of FIG. 1; and,

FIG. 8 is a right side view of FIG. 1.

1 Claim, 8 Drawing Sheets(56)
